UNITED STATES PATENT OFFICE.

DAVID H. FOREMAN, OF DENVER, COLORADO.

LOCOMOTIVE-HEADLIGHT CLEANER.

SPECIFICATION forming part of Letters Patent No. 693,319, dated February 11, 1902.

Application filed August 24, 1901. Serial No. 73,154. (No model.)

To all whom it may concern:

Be it known that I, DAVID H. FOREMAN, a citizen of the United States of America, residing at Denver, in the county of Arapahoe and State of Colorado, have invented certain new and useful Improvements in Locomotive-Headlight Cleaners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an attachment for locomotive-engines, and applies more particularly to the headlight of same, being designed to remove and prevent the accumulation of snow, dust, and like obstructions from 20 the glass of the headlight and in like manner from the front windows of the cab. The arrangement is such that this result can be effected at any necessary time by the engineer or fireman from the cab of a running 25 engine.

It is well known that in practice, with a locomotive running into a heavy snow-storm, the flying snow will accumulate upon the glass of the headlight and obscure the same 30 to an extent seriously diminishing its lighting efficiency and in like manner lodge upon and obscure the front cab-windows, cutting off the enginemen's outlook and rendering operations upon a night run under these conditions extra hazardous, seriously endangering 35 the safety of both persons and property. The appliance illustrated in the accompanying drawings, when charged with air, steam, or other suitable fluid under high pressure, is 40 designed to prevent these conditions from arising without in any degree diminishing the efficiency of the operative functions of the headlight.

Having briefly outlined the construction, 45 as well as the objects it is designed to accomplish, I will proceed to describe the same in detail, reference being made to the accompanying drawings, in which—

Figure 1 is a side elevation of one form in 50 the headlight attachment, showing also in broken-outline figure the adjacent parts of the locomotive to which it is attached. Fig.

2 is a corresponding front elevation of the attachment shown in Fig. 1. Fig. 3 is a plan view of a similar attachment arranged for 55 both headlights and front cab-windows. Fig. 4 is a side elevation of the same. Fig. 5 is a front elevation, in a slightly-modified form of construction, of a similar attachment for headlights. Fig. 6 is a side elevation of one 60 form of the headlight attachment and a part of the locomotive, showing the use of the tubular hand-rail of the locomotive in conjunction with the headlight attachment.

The same reference characters indicate the 65 same parts in all the views.

Suitably mounted adjoining the side of the headlight-glass, as shown in Figs. 1 and 2, or above and in front of the same, as shown in Figs. 3 and 4, is an enlarged vent-tube 2, in 70 which are formed orifices or perforations 2^a, of any preferred shape or number. These orifices are distributed over a part of the vent-tube in varying planes, causing the fluid under compression in being emitted from them 75 to be scattered over the glass at varying angles, as indicated by arrow-lines in Figs. 3 and 4. This vent-tube is suitably connected at one end, as in Figs. 1 and 2, with a connecting-tube 3, disposed longitudinally above 80 the boiler or in any other most convenient position and suitably supported, as at 3^a. The rear end of the tube 3 is carried into the engine-cab, where it is fitted with a valve 4, from which a supply-tube 5 is carried to and 85 connected with any convenient storage of air, steam, or other suitable fluid under constant high pressure. Where the engine construction is such as to admit of it, if preferred the hand-rail tube A can be utilized in making 90 the connection between the cab-valve 4 and the headlight vent-tube 2 with the usual reducing-unions, &c., as shown in Fig. 6 at A' and A², thus dispensing with the connecting-tube 3, thereby reducing cost and avoiding 95 the encumbering of the locomotive with extra attachments.

The headlight vent-tubes can be arranged vertically, as in Figs. 1 and 2, or horizontally, as in Figs. 3 and 4, as may be preferred. In 100 Figs. 3 and 4 are also shown two upright vent-tubes 2¹ 2², placed adjoining the front cab-windows and connected with the valve 4 by tubes 6 and 7, respectively. In this arrange-

ment the valve 4 should be of any convenient construction of switching or three-way design, permitting the connection to be made with either or all vent-tubes, as occasion may require.

A further modification in the construction of the headlight attachment is shown in Fig. 5, wherein the vent-tube 2° is in the form of an arc of a circle arranged concentric with the headlight center and supported upon one or both sides by upright connecting-tubes 3°, which connect with the cab-tube 3 by a cross-tube 3°.

Having thus described my invention, what I claim is—

1. In an apparatus for cleaning the outer surface of transparent devices, the combination with a source of compressed air, of means connected with the air source, mounted in proximity to the transparent device, and having outlets disposed in varying planes and arranged to discharge the air across the face or exterior surface of the glass at different angles for the purpose set forth.

2. In a locomotive-headlight cleaner, the combination with a source of compressed fluid, of a perforated pipe arranged in proximity to the lens or glass of the light, but not obscuring its rays, the perforations of the pipe being disposed in varying planes to deliver jets of fluid across the outer surface of the lens or glass at different angles, a conduit leading from the fluid source to said perforated pipe, and a controlling-valve connected with the pipe and accessible to the engineers without leaving the cab.

3. In a locomotive-headlight cleaner, the combination with a source of compressed

fluid, of a pipe arranged part way around the glass or lens of the light, and in suitable proximity thereto, but not obscuring its rays, the said pipe being connected with a fluid source, and provided with orifices arranged in varying planes to deliver fluid-jets across the face or outer surface of the glass or lens at different angles for the purpose set forth.

4. In an apparatus for cleaning the outer surface of transparent devices, the combination with a source of compressed air, of means connected with said air source and having a suitable outlet, said means being located to direct the air across the outer surface of the transparent device, and arranged so as not to obscure the rays of light passing therethrough.

5. In a locomotive-headlight cleaner, the combination with a source of compressed fluid, of a pipe connected with said fluid source, arranged in proximity to said headlight, and perforated in varying planes causing the fluid-jets to be delivered across the outer surface of the glass or lens at different angles.

6. In a locomotive-headlight cleaner, the combination with a source of compressed fluid, of a perforated pipe mounted in suitable proximity to the headlight, and a conduit leading from the source of fluid to said perforated pipe, the tubular hand-rail of the locomotive forming a part of said conduit.

In testimony whereof I affix my signature in presence of two witnesses.

DAVID H. FOREMAN.
